UNITED STATES PATENT OFFICE.

JOHN F. HUDEC, OF CLEVELAND, OHIO.

INVALID-SUPPORT.

1,010,261.

Specification of Letters Patent. Patented Nov. 28, 1911.

Application filed April 10, 1909. Serial No. 489,097.

To all whom it may concern:

Be it known that I, JOHN F. HUDEC, a citizen of the United States, residing at Cleveland, in the county of Cuyahoga and State of Ohio, have invented a certain new and useful Improvement in Invalid-Supports, of which the following is a full, clear, and exact description, reference being had to the accompanying drawings.

This invention has for its object to provide a device for supporting an invalid or convalescent person confined to the bed in an inclined position.

The support herein shown permits the adjustment of the device to support the patient in varying degrees of reclining position and also is so constructed that the whole device may be folded into a compact package which may be stored without taking up much room.

Generally speaking, the invention comprises an element which combines the two essential parts of the device.

Reference is now made to the drawings of the accompanying patent application:

Fig. 1 is a perspective view showing the device in a position of reclining at an angle of about 45° to the horizontal; Fig. 2 is a side elevation showing the device in a horizontal position; Fig. 3 is a side elevation showing the device in a position of reclining at an angle of about 75° to the horizontal; Fig. 4 is a top plan view; Fig. 5 is a top plan view showing the device in a folded position.

This support is a combination of the two essential parts of the device, namely, a base or frame which supports the patient in an inclined position, and a device which permits the patient to recline in a horizontal position.

Upon this base or frame is mounted a device which has a horizontal support which is hinged to the base, so that it will fold up into a horizontal position.

This support is a combination of a base or frame which is hinged to the base, so that it will fold up into a horizontal position.

and upon the manipulation of the latch the table top may be swung about its pivot 6 and when the device is folded to occupy a position parallel with the arm 4 as indicated in Fig. 5.

Toward the rear ends thereof the pieces 1 and 2 are provided with ribs 9 which are spaced apart and provide a wedge shaped opening between each pair of the same. Co-operating with the ribs 9 are members 10 which are wedge shaped in cross section and are formed to fit the space between the pairs of ribs 9. Upon these members 10 are secured other members or blocks 11, which are fastened upon the members 10 by means of hinges 12.

Upon the members 11 is mounted a back 13, the same being pivoted upon pins 14, as shown in Fig. 2. This provision of thus permitting the back 13 to be pivoted to the back 13 permits the adjustment of the back 13 to a horizontal position.

The device is supported by the base 1 and 2, which is provided with a middle rib 10, which is spaced from the side ribs 9, so that the device may be supported in a horizontal position. The middle rib 10 is provided with a slot 15, through which a pin 16 is passed, so that the device may be supported in a horizontal position.

The device is supported by the base 1 and 2, which is provided with a middle rib 10, which is spaced from the side ribs 9, so that the device may be supported in a horizontal position.

The device is supported by the base 1 and 2, which is provided with a middle rib 10, which is spaced from the side ribs 9, so that the device may be supported in a horizontal position.

The device is supported by the base 1 and 2, which is provided with a middle rib 10, which is spaced from the side ribs 9, so that the device may be supported in a horizontal position.

The device is very efficient for the purpose for which it is intended, and due to the detachable structure it may be built around the patient in bed if the patient is not sufficiently convalescent to be moved. This is quite an important feature.

It will be further observed that the back is adjustable with respect to the arm supports, which is quite important in that the 10 arms may always be supported in substantially a horizontal position no matter to what degree the patient may be reclining.

Various modifications may be made in the parts of the device without departing 15 from the spirit of this invention and I do not limit myself further than the express language of the claims.

Having thus described my invention, what I claim is:

- 20 1. An invalid support comprising a pair of side pieces, a pair of ribs mounted upon each of the side pieces, a back member supported between said rib members and removable therefrom by a sliding movement.
- 25 2. In an invalid's support, a pair of side pieces, a pair of ribs carried by each of said members and providing a wedge shaped space between each pair, wedge shaped members slidably engaging the said ribs, 30 and a back mounted upon said members.
- 35 3. In an invalid's support, a pair of side pieces, a pair of ribs upon each of said side pieces, members slidably engaging the said ribs, and a back pivotally supported upon the said members.
- 40 4. In an invalid's support, a pair of side pieces, members removably supported by said side pieces, other members hinged upon the first mentioned members, a back pivoted upon the last mentioned members, and means for supporting the back in any degree of inclined position.
- 45 5. In an invalid's support, a pair of side

pieces, a pair of ribs upon each of the said side pieces, members removably supported by said ribs, other members hinged upon the first mentioned members, a back pivoted upon the last mentioned members, and means coöperating with the side pieces for supporting the back in varying degrees of inclined 50 position.

6. In an invalid's support, a pair of side pieces, members removably supported by said side pieces, other members hinged upon the first mentioned members, a back pivoted 55 upon the last mentioned members, said back being formed in two parts hinged together, whereby the same may be folded.

7. In an invalid's support, a pair of side pieces, arm rests hingedly mounted upon 60 said side pieces, members removably supported by the said side pieces, other members hinged upon the first mentioned members, a back pivoted upon the last mentioned members, said back being formed in 65 two parts hingedly secured together, whereby the whole device may be folded.

8. In an invalid's support, a pair of side pieces, a back supported by said side pieces, means for supporting the back in varying 70 degrees of inclined position and a member extending transversely of the support from side piece to side piece for the purpose of engaging the limbs of the user.

9. In an invalid support comprising a 75 pair of upright side plates each provided at its rear portion with a laterally extending foot, a back member carried by the side pieces, and arm rests independently carried by the two side pieces.

In testimony whereof, I hereunto affix my signature in the presence of two witnesses.

JOHN F. HUDEC.
